DESIGN FOR A DISH

Louise Lowndes King, Washington, D. C.

Application August 1, 1945, Serial No. 121,146

Term of patent 14 years

(Cl. D44—10)

To all whom it may concern:

Be it known that I, Louise Lowndes King, a citizen of the United States of America, residing at Washington, in the District of Columbia, have invented a new, original, and ornamental Design for Dishes, of which the following is a description, reference being had to the accompanying drawing, forming part thereof.

I claim:

The ornamental design for a dish, as shown.

LOUISE LOWNDES KING.
